UNITED STATES PATENT OFFICE

166,182

EVAPORATIVE COOLER

Adam D. Goettl, Phoenix, Ariz.

Application September 18, 1951, Serial No. 16,676

Term of patent 7 years

(Cl. D62—4)

To all whom it may concern:

Be it known that I, Adam D. Goettl, a citizen of the United States, residing in the city of Phoenix, State of Arizona, have invented a new, original, and ornamental Design for an Evaporative Cooler, of which the following is a specification, reference being had to the accompanying drawing, forming a part hereof.

Figure 1 is a top perspective view of an evaporative cooler showing my new design.

Figure 2 is a front perspective view thereof.

Figure 3 is a rear perspective view thereof.

Figure 4 is bottom plan view thereof.

I claim:

The ornamental design for an evaporative cooler, as shown.

ADAM D. GOETTL.
